UNITED STATES PATENT OFFICE.

CHASE W. WOLFE, OF MILWAUKEE, WISCONSIN, ASSIGNOR TO THE FISK RUBBER COMPANY, OF CHICOPEE FALLS, MASSACHUSETTS, A CORPORATION OF MASSACHUSETTS.

DESIGN FOR A TIRE.

Application filed October 16, 1922. Serial No. 3,984. Term of patent 14 years.

To all whom it may concern:

Be it known that I, CHASE W. WOLFE, a citizen of the United States, residing at Milwaukee, in the county of Milwaukee and State of Wisconsin, have invented a new, original, and ornamental Design for a Tire, reference being had to the accompanying drawing, which forms a part thereof, and in which—

Figure 1 is a side elevation of a tire embodying my design, while Figures 2 and 3 are sections on the lines 2—2 or 3—3 of Figure 1.

I claim: The ornamental design for a tire substantially as shown.

CHASE W. WOLFE.
